UNITED STATES PATENT OFFICE.

ROBERT H. WORRALL, OF WASHINGTON, DISTRICT OF COLUMBIA, ASSIGNOR TO WIRED RADIO, INC., OF NEW YORK, N. Y., A CORPORATION OF DELAWARE.

CRYSTAL CALIBRATOR HARMONIC SELECTOR AND AMPLIFIER CIRCUIT.

Application filed October 28, 1927. Serial No. 229,481.

My invention relates broadly to harmonic selector circuits and more particularly to a circuit arrangement for a piezo electric crystal controlled calibrator system and amplifier.

One of the objects of my invention is to provide a circuit arrangement for a crystal calibrator harmonic selector and amplifier wherein the particular harmonic which is being utilized may be readily determined.

Another object of my invention is to provide a coupling system between the output circuit of the piezo electric crystal controlled oscillator and a detector system of such character that the particular harmonic to which the circuit responds may be readily selected without the necessity of resorting to a wave or frequency meter.

Other and further objects of my invention reside in the circuit arrangements described in the specification hereinafter following by reference to the accompanying drawings wherein:

Figure 1 shows diagrammatically the crystal calibrator circuit of my invention; Fig. 2 is a modified wiring diagram of a crystal calibrator embodying my invention; Fig. 3 shows the principle of my invention as applied to a conductive-capacitive coupling system between a crystal controlled oscillator and a detector; and Fig. 4 shows the application of the calibrator circuits of my invention to a measuring device for incoming signaling frequency in a signal receiving circuit.

In crystal calibrator circuits the harmonics of a crystal fundamental frequency are generated in the plate circuit inductance of an electron tube system, and the beats resulting from another frequency heterodyning with a harmonic can be detected and amplified through the medium of a detector and audio amplifier attached for calibration purposes.

In prior types of crystal calibrator circuits the harmonics have been impressed upon an untuned grid circuit of a detector tube. These types of calibrators while obtaining the desired results have the disadvantage of the operator not knowing which harmonic he is listening to nor what the frequency is unless the apparatus has been previously calibrated. If the apparatus had never been calibrated it would be necessary to resort to the use of some calibrated wave meter or frequency

meter at least once for each coil calibrated and preferably calibration should be oftener.

In the circuit arrangement of my invention I provide a detector circuit for a crystal controlled calibrator wherein the detector has a tuned grid system and the operator can tell at a glance just what harmonic he is on by reference to the condenser setting and the position of the tap on the associated inductance.

Figure 1 of the drawings shows three circuits; a crystal oscillating circuit 1, a detector circuit 2 and an amplifier circuit 3.

The crystal circuit includes the quartz crystal 4 which is the frequency control for tube system 1; a grid leak 5; a by-pass condenser 6 and an inductance 7 connected in the tube circuits with batteries A and B in the manner shown.

The detector circuit 2 consists of a grid circuit including a tapped inductance 8, a variable condenser 9 and a grid condenser 10 shunted by a grid leak 11. A coupling lead 25 and condenser 12 are connected to the grid circuit as shown; and the plate circuit which includes the primary of an audio frequency transformer 14 is shunted by a condenser 15 connected to the tube circuit and battery as shown.

Fig. 2 is a modification of Fig. 1 showing how a parallel feed circuit 17 to the oscillator plate circuit may be supplied, and also showing a different method of grid leak return and how the condenser 10 acts both as a grid condenser and a control device by reason of its variable properties.

Figure 3 is another modification of Fig. 1 whereby the coupling from the crystal circuit to the grid circuit of the detector tube 2 through the medium of coils 7 and 8 is eliminated and a method of conductive-capacitive coupling is used whereby condenser 9 in this case tunes a part, or all, as the case may be, of inductance 7 and this tuned circuit coupled to the grid of the detector tube 2 through the condenser 10, which also functions as a grid condenser. 6 indicates a by-pass condenser across the B battery, 11 shows a grid leak or any method of grid bias, and 12 represents the coupling condenser as described in Fig. 1.

Figure 4 contains an auxiliary circuit for the reception of weak signals from a distant source. That is, the radio frequency amplifier signal receiving circuit 18 may connect

with antenna 19 and tuning condenser 20. The radio frequency amplifier constituting the receiving circuit includes in its output the coil 21 and condenser 22. The remainder of

5 the detector circuit is the same as in Fig. 1. Condenser 23 is a coupling condenser for coupling coil 7 to the detector tube circuit.

In the drawings the quartz crystal 4 is so chosen that its harmonics fall close enough 10 together to give a sufficient number of different operating frequencies. Coil 7 is of such a value that the crystal will oscillate and at the same time the coil itself will be rich in the required harmonics. This means 15 the coil 7 must have a large inductance to capacity ratio. Any of the common methods of grid bias such as the grid leak 11, or a choke and negative biasing battery may be used to maintain the grid at the proper operating 20 potential to give a distorted wave form which results in the generation of required harmonics.

In Figures 1 and 2 these harmonics are transferred by means of inductive coupling 25 to the inductance 8, the circuit consisting of a coil 8 and variable condenser 9, hereinafter referred to as the detector grid circuit, which may be tuned to any harmonic of the crystal fundamental frequency.

30 The coupling post or lead 25 brings in any radio frequency impressed upon it through the condenser 12 to the grid circuit of the detector tube 2. If the incoming frequency is nearly the same as the crystal harmonic frequency to which the grid circuit is tuned, these 35 two frequencies will produce a beat which is the difference between the two frequencies, which beat will be impressed upon the grid of the detector tube, 2, and the resulting audio 40 frequency amplified through the medium of one or more stages of audio amplification 3 and then transferred to telephones 16 or to a visual indicating device for noting the beat frequency.

45 In Figure 3 the harmonics are selected by tuning a part of coil 8 with the condenser 9 and transferring the harmonic to the grid of the detector 2 through the medium of condenser 10, which functions both as a grid condenser and a coupling condenser.

In Figure 4 the harmonic selection is done on the incoming frequency and not on the crystal frequency through the inductive coupling between coils 21 and 8. The tapped coil 55 7 in this case assists in controlling the strength of the crystal frequency impressed upon the detector tube 2 through the medium of the coupling condenser 23.

There are a number of advantages arising 60 out of the use of this type of circuit, among which may be mentioned:

(a) The ability to select and amplify any harmonic of the crystal with a knowledge of what harmonic frequency is;

65 (b) Any oscillating receiver, transmitter or

frequency meter may be calibrated directly from the calibrator without the medium of any wave meter or frequency meter;

(c) Frequency meters or receivers need not be calibrated until they arrive at their 70 destination, provided they have a crystal calibrator harmonic selector;

(d) Through the medium of the circuit shown in Fig. 4 any distant station supposed to be on a given frequency can be set on 75 its proper frequency, by calibrating the transmitter on the harmonic either side of the given frequency, directly, without having to go through the medium of a receiver.

(e) In the present type of crystal calibrator 80 circuits the resulting audio frequency signal is sometimes very weak, while with the harmonic selector circuit this signal strength is greatly increased.

By use of my invention a means is provided whereby specific desired harmonics, provided they are known to be present in the plate inductance of the crystal calibrator circuits, regardless of the method used to secure a distorted wave form in the plate circuit, can be selected and transferred to a detector circuit, whereby the beat resulting from another frequency heterodyning with the harmonic may be detected and amplified.

While I have described my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. In a harmonic selector and amplifier systems, a piezo electric crystal element, a thermionic tube circuit connected with said piezo electric crystal element and arranged to generate harmonics of the fundamental frequency of said piezo electric crystal element, a detector tube circuit coupled with said thermionic tube circuit and calibrated in terms of the harmonics of the fundamental frequency of said piezo electric crystal element, and means for observing a beat frequency between the harmonic of said piezo electric crystal element and an oscillating circuit whose frequency is to be determined.

2. In a crystal controlled calibrator harmonic selector and amplifier system, a piezo electric crystal element, a thermionic tube 120 circuit for generating harmonics of the fundamental frequency of said piezo electric crystal element, a circuit comprising means for selecting, detecting and amplifying a selected harmonic frequency coupled with 125 said electron tube circuit and calibrated in terms of the harmonic frequencies of the fundamental frequency of said piezo electric crystal element, means connected to said second mentioned circuit for impressing a radio 130

- frequency voltage upon said second mentioned circuit, and a signal observing circuit to be actuated by the beat frequency between a selected harmonic of the fundamental frequency of said piezo electric crystal element and the frequency of the voltage impressed upon said second mentioned circuit.
3. A crystal controlled calibrator harmonic selector and amplifier system comprising a piezo electric crystal element, a thermionic tube circuit connected with said piezo electric crystal element and arranged to generate harmonics of the fundamental frequency of said piezo electric crystal element, a circuit comprising means for selecting, detecting and amplifying a selected harmonic frequency coupled with said thermionic tube circuit and calibrated in terms of the harmonic frequencies of said piezo electric crystal element, and means for impressing current of unknown frequency upon said last mentioned circuit from a circuit whose frequency characteristic is to be determined for observing a beat frequency between the selected harmonic and the unknown frequency.
4. In a crystal controlled calibrator harmonic selector and amplifier circuit, a piezo electric crystal element, a thermionic tube circuit connected with said piezo electric crystal element for generating predetermined harmonics of the fundamental frequency of said piezo electric crystal element, a tuned circuit coupled with said thermionic tube circuit and calibrated in terms of the fundamental frequency of said piezo electric crystal element, a detecting and observing circuit connected with said tuned circuit and means for impressing current whose frequency is to be determined upon said tuned circuit for deriving a beat frequency with a selected harmonic of the fundamental frequency of said piezo electric crystal element.
5. In a crystal controlled calibrator harmonic selector and amplifier circuit, a piezo electric crystal element, a thermionic tube circuit connected with said piezo electric crystal element for generating selected harmonics of the fundamental frequency of said piezo electric crystal element, a tuned circuit comprising an inductance and a variable capacity connected with said thermionic tube circuit and adjustable to be in resonance with any selected harmonic frequency of the fundamental frequency of said piezo electric crystal element, a detecting and amplifying system connected with said tuned circuit and means connected to said tuned circuit for receiving high frequency oscillations, the frequency of which is to be determined and deriving a beat frequency with respect to a selected harmonic for actuating said detecting and amplifying system and determining the frequency of the current thus impressed upon said tuned circuit.

ROBERT H. WORRALL.
